UNITED STATES PATENT OFFICE

CLARENCE H. SANDERSON, OF NUTLEY, NEW JERSEY, ASSIGNOR TO GENERAL ELECTRIC COMPANY, A CORPORATION OF NEW YORK

ELECTRIC SWITCH

Application filed April 29, 1924, Serial No. 709,894.

My invention relates to improvements in electric switches and more particularly to improvements in electric switches and circuit breakers for selectively controlling a plurality of circuits.

In the control of multiple bus D. C. systems wherein a plurality of switching devices such as circuit breakers are used to shift a source from one bus to another and to inter- 10 connect the buses, one or more of the circuit breakers are always in the circuit opening position. Consequently, the movable contacts, such as brushes, the contact faces of which are usually oblique when in the circuit opening position, are subject to dust accumulations which greatly impair their efficiency. With currents often as large as 20,000 amperes, this is especially troublesome and it becomes necessary frequently to 15 dress the contact faces of the movable contacts. Moreover, with such large currents, it is customary to employ a plurality of movable contacts or brushes to obtain the required conducting capacity. Where these 20 are rigidly mounted on one support, nicety of alinement is practically an absolute necessity for good contact.

With a plurality of brushes all mounted on one side of the switch supporting structure, the shocks which accompany the movements of the brushes, particularly to circuit closing position, tend to induce high stresses in the switch supporting structure. This 25 usually comprises panels of slate, marble and the like which do not inherently possess such static properties as satisfactorily and economically to withstand these stresses. Moreover, the brushes are usually under considerable stress when in the circuit closing position 30 so that bending stresses are imposed on the switch supporting structure. Switch-board panels of insulating material such as slate, marble and the like, are therefore structurally not economical materials since they 35 must assume massive proportions to withstand the stresses involved. Moreover, a plurality of circuit breakers each having a plurality of brushes involves considerable expense and much space. With a solid back 40 switchboard, the proper ventilation is diffi-

cult to obtain and it is necessary to reduce the current per unit area of brush contact or to space the brushes farther apart to prevent undue heating. This involves higher copper expense or more space. The space 45 factor becomes a highly important economic matter particularly in large cities where distributing stations have to be located on valuable property sites. Obviously all of these difficulties are cumulative and tend to increase the cost of electricity to the consumer, and particularly so, if the consumer is located in a densely populated district, so that the whole matter is a question of economic 50 importance to the public.

An object of my invention is to provide an improved electric switch which is adapted to be operated to control a plurality of circuits selectively and which is capable of conducting large currents with minimum 55 copper and maximum ventilation. Another object of my invention is to provide a plural circuit controlling electric switch which is particularly adapted for the control of multiple bus systems so that the movable contact member is normally in circuit closing position. A further object of my invention is to provide an electric switch having a plurality of flexibly mounted movable contacts arranged to insure a highly efficient contact and 60 to reduce shocks and strains on the supporting structure. A further object of my invention is to provide a compact unitary switch structure which has a power operated means for moving the movable switching element to any selected circuit controlling position, a power operated means for moving the movable switching element to circuit closing position and a relatively simple operating control.

My invention will be better understood from the following description taken in connection with the accompanying drawings and its scope will be pointed out in the appended claims.

Fig. 1 illustrates in perspective an electric switch embodying my invention and Fig. 2 illustrates in perspective another embodiment of my invention.

The switch embodying the form of my in-

100

vention shown in Fig. 1 comprises a plurality of spaced stationary contacts 1, 2, 3, and one or more cooperating movable contacts such as brushes 4 and 5 which are arranged to be positioned selectively for movement into circuit closing position with any one of the contacts 1, 2, 3, by an actuating mechanism comprising, for example, a motor 6, gears 7 and 8 and a screw shaft 9 so as to control a plurality of circuits. For moving the brushes 4 and 5 into circuit closing position when they have been placed in juxtaposition with any one of the contacts 1, 2 and 3, any suitable power operated mechanism which may be of the latched-in collapsible type, may be used. As shown, this mechanism comprises two pivoted brush or contact carrying arms 10, an operating toggle comprising links 11, a lost motion operating link 12, a holding 20 toggle comprising links 13, and 14, and a latch 15 therefor. This mechanism may be arranged to be actuated by any suitable means such as an electric motor 16 which may be arranged to move the link 12 through any suitable driving means such as a magnetic clutch 17, gears 18 and 19 and a loose crank 20.

The stationary contacts 1, 2 and 3 are mounted on and insulated from a suitable frame or structural member such as a bar 21 which may be of steel and which may be mounted in any suitable manner to support the entire switch. Rigidly associated with the bar 21 through insulators 22 are contact bars or buses 23 and 24 which are insulated from each other and spaced from the contacts 1, 2 and 3 to permit the brushes 4 and 5 to bridge either contact bar 23 and contacts 1 or 2, or contact bar 24 and contact 3 so as to control a plurality of circuits. In the particular arrangement shown, the contact bar 23 is continuous for two circuit controlling positions of the brushes 4 and 5 so that a source 25, which may be a D. C. generator or 45 rotary converter and which is connected to the contact bar 23, can be connected, with the brushes 4 and 5 in circuit closing position on contact 1 and contact bar 23 to a bus 26 or with the brushes 4 and 5 in circuit closing 50 position on contact 2 and contact bar 23 to a bus 27. Obviously the contact bar 23 could be made discontinuous, if it were desired to connect, for example, separate sources to the buses 26 and 27. With the brushes 4 and 5 55 in circuit closing position on contact 3 and contact bar 24, the buses 26 and 27 are interconnected. It is therefore possible to shift a source from one bus to another or tie two buses together, in accordance with the load 60 demand and in any case the brushes 4 and 5 are in contact closing position so that dust and dirt cannot accumulate on their contact faces.

In order that the brushes 4 and 5 may be moved to the various circuit controlling po-

sitions, they may be mounted on a suitable supporting means arranged for movement in line with the contacts 1, 2 and 3. The supporting means may comprise, for example, a carriage 28 reciprocable on a bed plate or 70 guide way 29 secured to and preferably insulated from the stationary contact supporting structure. The carriage 28 is arranged to be engaged by the screw shaft 9 which is rotatable in either direction by the motor 6 shown for example as a reversing field D. C. 75 motor.

The power operated mechanism for moving the brushes 4 and 5 to circuit closing position is mounted on the carriage 28. For controlling this mechanism so as to effect the movement of the brushes 4 and 5 to circuit opening position, I provide controlling means such as an electroresponsive device 30 arranged when energized to release the latch 15 so that the toggle 13, 14 may collapse and thus allow the brushes 4 and 5 to move oppositely away from contact closing position. 80

For controlling the travel of the carriage 28, limit switches 31, 32, 33, arranged to be actuated by a projection 34 mounted on the carriage, are provided. Collector rails 35, 36 and 37, arranged to be traversed by contact shoes or wheels 38, 39 and 40 mounted on the carriage 28 are provided for conducting current to various auxiliary circuits arranged to be supplied from control buses 41 and 42. Obviously, in place of the collector rails and contact wheels, there may be used a looped multiconductor control cable which has its several conductors connected to fixed terminals on the carriage and which has sufficient length in the loop to permit the maximum desired travel. 95

For controlling the actuating means comprising the motor 6 and the shaft 9, the power operated mechanism comprising the motor 16 and operating link 12 and the controlling means or electroresponsive tripping device 30, I provide a control switch 43 adapted to be operated to provide a definite or predetermined sequence of switching operations. Thus, assuming the switch or circuit breaker contacts 4 and 5 in circuit closing position and that it is desired to move to another circuit closing position, the sequence is; first, the tripping or opening of the contacts; second, moving the contacts to the desired position, and third, closing the contacts. The control switch 43 comprises a reciprocable member such as a rod 44 biased to a neutral or intermediate position by any suitable means such as springs 45 and carrying bridging contacts 46, 47 and 48 arranged for engagement with cooperating fixed contacts such as contact segments 49, 50 and 51. The rod 44 may be restrained from rotary movement by a dog 52 until pulled out sufficiently to release the dog from registering slots in a fixed member such as a disk 53. 100 110 115 120 125 130

These slots are marked 1, 2 and 3 to correspond with the different positions of the contacts 4 and 5. For reversing the field connection to the motor 6, a flip switch 54 arranged to be operated by lugs projecting from a member 55 secured to the rod 44 may be provided, although an independently operable switch may be used. The contact 47 is arranged so that in pulling out on rod 44 it bridges contacts 50 before contact 46 touches contact 49 and some one of the co-operating contact segments marked 1, 2 and 3 to correspond with the different circuit controlling positions of the brushes 4 and 5.

Assuming the parts to be positioned as shown in Fig. 1 and that it is desired to shift the source 25 from bus 26 to bus 27, the control switch rod 44 is pulled out thus causing contact 47 to bridge contact segments 50. This completes a circuit from control bus 41 through conductor 56, contact segments 50 and bridging contact 47, conductor 57, collector rail 35, contact shoe 38, conductor 58, auxiliary switch 59 which is closed when the circuit breaker is closed, conductor 60, controlling device 30, conductor 61, contact shoe 39, collector rail 36 and conductor 62 to control bus 42. The circuit just traced constitutes the tripping or opening circuit, irrespective of the position of the brushes 4 and 5 and when closed energizes the controlling device 30 which trips the latch 15 thus allowing the brushes 4 and 5 to move to circuit opening position. Obviously, the controlling device 30 may also be arranged to be energized in response to abnormal circuit conditions in a manner well known to the art.

The rod 44 is now turned to position 2. In this movement the flip switch 54 is thrown to close contact 63 and contact 46 completes a circuit from control bus 41 through conductor 56, contact segment 49, contact 46, co-operating contact segment 2, conductor 64, limit switch 32, conductor 65, flip switch 54 and contact 63, conductor 66, motor field 6', armature of motor 6, conductor 67, collector rail 36 and conductor 62 to control bus 42. At the same time a parallel circuit through a suitable indicating device such as a lamp 68 is completed so as to indicate that the actuating means or travel motor 6 is energized and the brushes 4 and 5 are moving. When the carriage 28 reaches a position such that the brushes 4 and 5 are opposite the stationary contact 2, the projection 34 opens the limit switch 32, thereby interrupting the circuits of the travel motor 6 and the lamp 68. It is of course understood that the usual red and green lamps for indicating the closed and open positions respectively of the brushes 4 and 5 may be provided for as well as the white or travel indicating lamp 68, by the addition of more auxiliary switches on the traveling mechanism and more collector rails and contact wheels.

By analogy, the circuit for energizing the travel motor for movement of brushes 4 and 5 from position 2 to position 3 or from position 1 to position 3 may readily be traced. For reverse movement, the circuits will be obvious from the fact that the contact rod 44 is turned in the opposite direction so as to shift the position of the flip switch 54 to close on contact 69. In this way the motor field 6'' is put in circuit with the buses 41 and 42, thus reversing the direction of the motor 6 and the carriage 28.

To move the brushes 4 and 5 to contact closing position on the stationary contact 2 and contact bar 23, the control switch rod 44 is pushed in and contact 48 bridges contacts 51. This completes a circuit from control bus 41 through conductor 56, contact segments 51 and contact 48, conductor 70, collector rail 37, contact shoe 40, conductor 71, auxiliary switch 72 closed when the circuit breaker is open and vice-versa, conductor 73, magnetic clutch 17, motor 16, conductor 74, contact shoe 39, collector rail 36 and conductor 62 to control bus 42. The closing circuit just traced is the same, irrespective of the selected position to which the brushes 4 and 5 have been moved. The motor 16 is thus energized and caused to turn the gear 19, a projection on which engages the loose crank 20 so as to raise the operating link 12. This moves the brushes 4 and 5 into circuit closing position and sets the holding toggle 13 and 14 which is held rigid by the latch 15. The operating link 12 falls back slightly and opens the auxiliary switch 72, thus opening the circuit of the motor 16 and clutch 17. The switch rod 44 may now be released and will assume the intermediate position with dog 52 in slot 2 of the disk 53.

Referring now to the embodiment of my invention shown in Fig. 2, the spaced stationary contacts 1, 2 and 3 are mounted on and insulated from a supporting member 21 which is secured to end frame members 75, only one being shown, tied together for example by bottom frame members 76. The contact bars 23 and 24, insulated from each other as heretofore described, are insulated from and supported by the end frames 75. The movable contacts or brushes 4 and 5 are shown in pairs although as many as necessary to secure the desired current carrying capacity may be used. Each of the brushes 4 and 5 is independently pivoted on the brush arms 10 so that nicety of alignment in the brush contact faces is unnecessary in order to insure a good contact.

In this modification of my invention, the carriage 28, which is arranged for movement on the bottom frame members 76, carries not only the movable brushes 4 and 5 and the power operated mechanism comprising the motor 16 for moving them to circuit closing position, but also the actuating means, which

is adapted to be operated to position the brushes 4 and 5 selectively. This actuating means comprises the motor 6 arranged to drive a worm wheel 77 journaled on the carriage 28 and threaded for engagement with a screw member or rod 78, the ends of which are mounted in the end frames 75 so as to prevent turning but with sufficient lost motion to allow for slight deviations in alignment.

Limit switches 31, 32 and 33 arranged to be actuated by a projection 34 on the carriage 28 are provided as before, the limit switch 32 comprising two insulated portions arranged to control two contacts 79 and 79' respectively. The carriage is also provided with a position switch 80 arranged to engage interconnected spaced contacts 81, 82 and 83 in the respective positions of the carriage. In view of the fact that the travel motor 6 is mounted on the carriage 28, a collector rail 84 is provided in addition to the collector rails 35, 36 and 37 and likewise a contact shoe 85 is provided in addition to the contact shoes 38, 39 and 40.

For controlling the actuating means comprising the travel motor 6, the power operated switching mechanism comprising the motor 16 and the controlling means comprising the tripping electroresponsive device 30, I provide a control switch which as illustrated comprises a reciprocable contact controlling member such as a rod 44 and a rotatable contact controlling member 86. The rod 44 is biased to an intermediate position by springs 45 and carries a bridging member 87 arranged when the rod is pulled out to bridge contacts 88 and when pushed in to bridge contacts 89 so as to effect respectively the tripping and closing of the circuit breaker. The contact controlling member 86 is arranged to control contacts marked 1', 2' and 3' to correspond with the different circuit closing positions of the brushes 4 and 5, and its handle may be arranged to move over a stationary dial mounted on a control switchboard and marked so that the position of the handle will indicate the position of the brushes. For controlling the direction of rotation of the travel motor 6, that is the direction of movement of the carriage 28, a reversing controller comprising energizing windings 90 and 91 may be used. This controller is arranged to control contacts 92, 93, 94 and 95 in various auxiliary circuits which will hereinafter be pointed out.

Assuming that the parts are positioned as shown in Fig. 2 and that it is desired to shift source 25 from bus 26 to bus 27 the operation is as follows:—The switch rod 44 is pulled out, thus completing a circuit from the control bus 41 through conductor 96, contact member 87 and contacts 88, conductor 97, collector rail 35, contact shoe 38, conductor 98, controlling means 30, conductor 99, aux-

iliary switch contacts 100 closed when the circuit breaker is closed, conductor 101, contact shoe 39, collector rail 36 and conductor 102 to control bus 42. The circuit just traced is the same for all circuit-closing positions of the brushes 4 and 5.

The switch rod 44 is now released and the switch member 86 turned clockwise until its contact arm 103 engages the right hand cooperating contact 2', thus completing a circuit from control bus 41 through conductor 96, contact 103, right hand contact 2', conductor 104, position switch 32 and contact 79, conductor 105, controller winding 91 and conductor 106 to control bus 41. Upon energization of the controller winding 91, a circuit is completed from control bus 41 through conductor 107, contact 92, conductor 108, contact rail 84, contact shoe 85, motor 6 and lamp 68 in parallel, contact shoe 40, collector rail 37, conductor 109, controller contact 93 and conductor 106 to control bus 42. The travel motor 6 is thus energized for rotation in a direction to move the carriage 28 to the right. So long as the controller winding 91 is energized, the carriage will be moved but as soon as the carriage 28 reaches a position where projection 34 actuates the limit switch 32, the circuit of winding 91 is interrupted and under the influence of suitable biasing means, such as springs, the controller is moved to open contacts 92 and 93 and the circuit of the motor 6 and lamp 68 interrupted. This occurs when the brushes 4 and 5 are in juxtaposition with the stationary contact 2.

In order to move the brushes 4 and 5 into circuit closing position, the switch rod 44 is pushed in, thus completing a circuit from control bus 41 through conductor 96 contacts 89 and contact member 87, conductor 110, contact 82, position switch 80, conductor 111, magnetic clutch 17, motor 16, auxiliary switch contacts 112 closed when the circuit breaker is open and vice-versa, conductor 101, contact shoe 39, collector rail 36 and conductor 102 to control bus 42. The motor 16 is thus energized and rotates the worm 113 and worm gear 114 in a direction such that a crank 115 secured to the worm wheel moves around and engages the loose crank 20. This latter is then turned and moves the operating link 12 upward thereby moving the brushes 4 and 5 to circuit closing position and setting the holding toggle 13, 14 which is held by the latch 15.

To move the brushes 4 and 5 from any position to another as from position 1 or 2 to position 3, that is where they may be closed on contact 3 to tie the buses 26 and 27 together, the procedure is analogous to that heretofore described except that the contact 103 is turned clockwise to engage its cooperating contact 3'.

Assuming that the brushes 4 and 5 are

closed on stationary contact 3 and contact 24 and that it is desired to change the circuit connection from interconnected buses so as to connect the source 25 to bus 27, the switch rod 44 is pulled out to complete the circuit of the controlling means 30 as heretofore described so as to effect the movement of the brushes to circuit opening position. The switch member 103 is then turned clockwise from its cooperating contact 3' to its left hand cooperating contact 2' thus completing a circuit from the bus 41 through conductor 96, contact 103 and its left hand cooperating contact 2', conductor 116, contact 79' of limit switch 32, conductor 117, controller winding 90 and conductor 106 to bus 42. The controller is thus energized and contacts 94 and 95 thereof closed, thus completing a circuit from control bus 41 through conductor 107, contact 94, conductor 109, collector rail 37, contact shoe 40, motor 6 and lamp 68 in parallel, contact shoe 85, conductor 108, controller contact 95 and conductor 106 to control bus 42. The direction of current in the field of the motor 6, which may be a shunt field direct current motor, is therefore reversed so that the motor will move the carriage 28 from right to left. When the projection 34 engages the limit switch 32, the controller winding 90 will be deenergized and consequently the circuit of the motor 6 interrupted. The brushes 4 and 5 may then be moved to circuit closing position by pushing in the control switch rod 44 as heretofore described.

It will be obvious from the open construction embodied in the modifications of my invention shown in Figs. 1 and 2 that the maximum ventilation is assured so that the brushes 4 and 5 need not be excessive in size to avoid heating and therefore the current intensity may be greatly increased as compared with solid back switchboard mountings.

It is also obvious that because of the opposed arrangement of the brushes 4 and 5 that the desired conductivity, even for heavy currents, may be obtained with the movable contacts concentrated in a relatively small space. Moreover, when the movable contacts or brushes are in circuit closed position, the contacts between them are in direct compression, for which the static properties of the materials used are best adapted, and this applies even though the brushes were to close on contacts mounted on slate and like materials. Furthermore, as the brushes come to circuit closing position simultaneously from opposite sides of the stationary contacts, the shocks are practically neutralized.

While I have shown and described in detail several modifications of my invention and described its application particularly to the control of multiple bus direct current systems, it is obvious to those skilled in the art

that it is not limited to the particular application described and that changes may be made without departing from my invention. I therefore aim in the appended claims to cover all such modifications and variations as fall within the true spirit and scope of my invention. 70

What I claim as new and desire to secure by Letters Patent of the United States, is:—

1. In an electric switch of the class described, a plurality of spaced stationary contacts, a cooperating movable contact, a movable supporting means therefor, power operated means adapted to be operated to move said supporting means to position said movable contact selectively for movement into circuit closing position with any one of said stationary contacts, a power operated collapsible mechanism mounted on said supporting means and adapted to be operated to move said movable contact into circuit closing position with the selected stationary contact, and means adapted to be operated to collapse said mechanism whereby to effect the movement of said movable contact to circuit opening position. 80

2. In an electric switch of the class described, a plurality of spaced stationary contacts, a plurality of cooperating contacts movable into juxtaposition with any one of said stationary contacts and oppositely movable into circuit closing position therewith, actuating means adapted to be operated to position said movable contacts selectively for movement into circuit closing position with one of said stationary contacts, and a power operated mechanism adapted to be operated to move said movable contacts into circuit closing position with the selected stationary contact. 100

3. In an electric switch of the class described, a plurality of spaced stationary contacts, a cooperating movable contact, movable supporting means therefor, power operated means adapted to be operated to move said supporting means to position said movable contact selectively for movement into circuit closing position with any one of said stationary contacts, and power operated mechanism mounted on said supporting means and adapted to be operated to move said movable contact into circuit closing position with the selected stationary contact. 110

4. In an electric switch of the class described, a frame, a plurality of spaced stationary contacts mounted thereon, a cooperating movable contact, a carriage supported by said frame and carrying said movable contact, power operated means adapted to be operated to position said carriage selectively whereby to place said movable contact into juxtaposition with any one of said stationary contacts, a power operated mechanism for actuating said movable contact mounted on said carriage and adapted to be operated to 120 125 130 135 140 145 150 155 160 165 170 175 180 185 190 195 200 205 210 215 220 move said movable contact into circuit closing position with the selected stationary contact, and means for controlling said mechanism whereby to effect the movement of 5 said movable contact to circuit opening position.

5. In an electric switch of the class described, a frame, a plurality of spaced stationary contacts mounted thereon, a cooperating movable contact, a carriage supported by said frame and carrying said movable contact, actuating means mounted on said carriage and adapted to be operated to position said carriage selectively whereby to 10 place said movable contact into juxtaposition with any one of said stationary contacts for movement into circuit closing position therewith, a power operated mechanism for actuating said movable contact mounted on said 15 carriage and adapted to be operated to move said movable contact into circuit closing position with the selected stationary contact.

6. In an electric switch of the class described, a frame, a plurality of spaced stationary contacts mounted thereon, a cooperating movable contact, a carriage supported by said frame and carrying said movable contact, actuating means mounted on said carriage and adapted to be operated to position 20 said carriage selectively whereby to place said movable contact into juxtaposition with any one of said stationary contacts for movement into circuit closing position therewith, a power operated mechanism for actuating said movable contact mounted on said carriage and adapted to be operated to move 25 said movable contact into circuit closing position with the selected stationary contact, and a control switch adapted to be operated 30 to control the operation of said actuating means and said mechanism in a definite sequence.

7. In an electric switch of the class described, a frame, a plurality of spaced stationary contacts mounted thereon, a plurality of cooperating contacts movable into juxtaposition with any one of said stationary contacts and oppositely movable into circuit closing position therewith, a carriage supported by said frame and carrying said movable contacts, actuating means adapted to be operated to position said carriage selectively whereby to place said movable contacts 50 in juxtaposition with one of said stationary contacts for movement into circuit closing position therewith, and a power operated mechanism mounted on said carriage and adapted to be operated to move said movable contacts into circuit closing position with the selected stationary contact, and electroresponsive 55 means adapted to be operated to effect the movement of said movable contacts to circuit opening position.

8. In an electric switch of the class described, a plurality of spaced stationary contacts, a plurality of contacts movable into juxtaposition with any one of said stationary contacts and oppositely movable into circuit 60

closing position therewith, actuating means adapted to be operated to position said movable contacts selectively for movement into circuit closing position with one of said stationary contacts, a power operated mechanism adapted to be operated to move said movable contacts into circuit closing position with the selected stationary contact, and means for controlling said mechanism adapted to be operated to effect the movement of 70 said movable contacts to circuit opening position.

9. In an electric switch of the class described, a plurality of spaced stationary contacts, a plurality of contacts movable into juxtaposition with any one of said stationary contacts and oppositely movable into circuit closing position therewith, actuating means adapted to be operated to position said movable contacts selectively for movement into circuit closing position with one of said stationary contacts, a power operated mechanism adapted to be operated to move said movable contacts into circuit closing position with the selected stationary contact, means 80 for controlling said mechanism adapted to be operated to effect the movement of said movable contacts to circuit opening position, and switching means adapted to be operated to control the operation of said actuating means, said mechanism and said controlling means in a definite sequence.

10. In an electric switch of the class described, a frame, a plurality of spaced stationary contacts mounted thereon, a plurality of cooperating movable contacts movable into juxtaposition with any one of said stationary contacts and oppositely movable into circuit closing position therewith, a carriage supported by said frame and carrying said movable contacts, actuating means adapted to be operated to position said carriage selectively whereby to place said movable contacts in juxtaposition with one of said stationary contacts for movement into circuit closing position therewith, a power operated mechanism mounted on said carriage and adapted to be operated to move said movable contacts into circuit closing position with the selected stationary contact, and electroresponsive 11 means adapted to be operated to effect the movement of said movable contacts to circuit opening position.

11. In an electric switch of the class described, a frame, a plurality of spaced stationary contacts mounted thereon, a plurality of cooperating movable contacts movable into juxtaposition with any one of said stationary contacts and oppositely movable into circuit closing position therewith, a carriage supported by said frame and carrying said movable contacts, actuating means adapted to be operated to position said carriage selectively whereby to place said movable contacts in juxtaposition with one of said sta- 12

tionary contacts for movement into circuit closing position therewith, a power operated mechanism mounted on said carriage and adapted to be operated to move said movable contacts into circuit closing position with the selected stationary contact, electro-responsive means adapted to be operated to effect the movement of said movable contacts to circuit opening position, and a control switch adapted to be operated to control the operation of said actuating means, said mechanism and said electroresponsive means in a definite sequence.

In witness whereof, I have hereunto set
15 my hand this 26th day of April, 1924.

CLARENCE H. SANDERSON.
